UNITED STATES PATENT OFFICE.

JOSEPH SAMUEL ELLIOTT, OF EDDY, TEXAS.

OVERALL JACKET OR WAIST.

1,300,938.

Specification of Letters Patent. Patented Apr. 15, 1919.

Application filed February 26, 1918. Serial No. 219,246.

To all whom it may concern:

Be it known that I, JOSEPH S. ELLIOTT, a citizen of the United States, and a resident of Eddy, in the county of McLennan and State of Texas, have made certain new and useful Improvements in Overall Jackets or Waists, of which the following is a specification.

My present invention relates generally to overall jackets or waists, my object being the provision of one, the construction of which permits of its formation with less material and its use with greater comfort and convenience than articles of this character now in common use.

In carrying out my invention I propose an overall jacket or waist terminating at its lower edge in a waist band, which, in use, is intended to be seated upon or lap the upper edges or portions of trousers sections, thus avoiding the extensions usually present with a waist section or jacket tucked into the trousers section.

My invention further proposes that the waist band above referred to be divided and utilized in connection with permanent belt sections rigidly attached to one of the sections of the band, and capable of performing its intended function either with or without engagement with the other section of the band.

My invention further purposes, in connection with this divided band structure, adjustment of the lower portion of the waist, or in other words, the adjustment of the waist-band, the adjustment being effected by the belt sections in connection with both of the waist band sections, the waist or jacket having side gussets to allow for the same.

In the accompanying drawing illustrating my present invention:

Figure 1 is a perspective view illustrating the practical application of my improvements, and,

Fig. 2 is a detailed perspective view looking at one side of the lower portion of the garment with the belt sections detached.

Referring now to these figures, my invention purposes a body garment in the nature of a waist or jacket generally indicated at 10, in Fig. 1, which is terminated at substantially the waist line of the wearer, and is provided with a waist band around its lower edge in front and rear sections 11 and 12.

Where the garment is buttoned down the

front, to provide for its assumption and removal, the front waist band section 11 is divided as shown particularly in Fig. 2, a lower button 13 and button hole 14 serving 60 to unite the sections in use.

The garment has side seams 15, the lower portions of which are divided between the waist band sections 11 and 12, and flexible gussets 16 inserted, in order that the opposing ends of the waist band sections 11 and 12 may be drawn together more or less in adjusting the waist band of the garment, for which reason it will be noted that the lower edges of the gussets are terminated 70 at the upper edges of the waist band sections. These gussets provide for the exclusion of air, dirt and other matter, when the waist band sections are extended, and obviate interference with adjustment of the 75 waist band, though entirely closing the garment at the waist line in its normal use.

The forward section 11 of the waist band has belt loops 17 and belt sections 18 and 19 are secured permanently to the ends of the 80 waist band section 12 as particularly seen in Fig. 2, the belt section 18 having a buckle 20 at its free end for adjustable engagement by the belt section 19, the latter having a row of apertures 21 adjacent its free 85 end. These belt sections 18 and 19 may be readily disposed through the belt loops 17 of the front section 11 of the waist band, and when so disposed they may be utilized to adjustably close the lower end of the garment in its lapped relation around the upper 90 portions of the trousers.

It is obvious, however, that with the construction described, I may in addition to the adjustable blouse forming means, readily 95 disassociate the belt sections 18 and 19 by removing them from the belt loops 17, and may engage these sections beneath and free of the front portion of the garment, so that the latter hangs loosely to permit free circulation of air upwardly beneath the same. At the same time it is to be observed that the rear portion of the garment to which the belt sections are permanently attached is still drawn tightly, or as tightly as desired, so that it is prevented from riding 100 upwardly when the wearer bends over.

A body garment of the present character utilized either as a shirt waist or overall jacket, will effect a considerable saving in 110 material as distinguished from those having the lower extensions necessary to be tucked

within the trousers, and in addition to this economy in material, provides for a more pleasing appearance, greater comfort in use, and a considerable range in adjustment for varying or changing climatic conditions. Thus when it is cool, it is obvious the lower portion of the garment may be completely closed while when uncomfortably warm its lower front may be free to provide, as above stated, for a free circulation of air.

I claim:

1. A body garment in the form of a waist or jacket, the lower edge of which terminates substantially at the waist line, and is divided into front and rear sections having connecting gussets, a waist band in front and rear sections, respectively, at the lower edges of the front and rear portions of the garment, and belt sections attached at one end to the opposite ends of the rear section of the waist band and engageable with and

disengageable from the front section of the waist band whereby the front section may be arranged to depend loosely over the belt for better ventilation, for the purpose specified. 25

2. A body garment in the form of a waist or jacket, the lower edge of which terminates substantially at the waist line, and is divided into front and rear sections having connecting gussets, a waist band in front and rear sections, respectively, at the lower edges of the front and rear portions of the garment, and belt sections attached at one end to the opposite ends of the rear section of the waist band, and over which the front section may loosely depend, said front section of the waist band having belt loops with which the belt sections may be associated. 30 35

JOSEPH SAMUEL ELLIOTT.
